H. MOLEND A.
VENTILATOR.
APPLICATION FILED APR. 23, 1921.

Patented Oct. 3, 1922.

H. Molenda
INVENTOR
BY
M. R. Reamy
ATTORNEY

UNITED STATES PATENT OFFICE.

HENRY MOLENDA, OF OLLIE, MONTANA.

VENTILATOR.

Application filed April 23, 1921. Serial No. 463,987.

To all whom it may concern:

Be it known that I, HENRY MOLENDA, a citizen of Poland, residing at Ollie, in the county of Fallon and State of Montana, have 5 invented certain new and useful Improvements in Ventilators, of which the following is a specification.

The main object of this invention is the provision of a ventilator fan having means 10 for closely regulating the draft thereof.

The above and other objects will become apparent in the description below, in which same characters of reference refer to same parts in the drawings.

15 Referring briefly to the drawing, Fig. 1 is a front elevational view, partly in section, of the device, in wide open position.

Fig. 2 is a side elevational view, partly in section, of the same.

20 Fig. 3 is a front elevational view of the same in maximum shut-off position.

Referring now in detail to the drawings, the numeral 1 represents binders or rivets rigidly connecting, in spaced-apart relation, 25 flat plates 2 and 9, the latter having a circular opening 8 therein, and the former having a similar circular opening surrounded by a cylindrical tube 3 integral with the plate 2. Within tube 3 are mounted brackets 4 supported upon a cross-bar 5, said brackets 4 having bearings therein in which is rotatably supported a shaft 7 upon which is mounted a propeller fan 6.

30 Shutters 10 of the form shown are pivotally mounted at 11 between the plates 2 and 9, and have small drums 12 rigid thereto about the pivotal axes. Cables 13 have their ends attached to said drums and are wound partly about the latter, and thence extend in

proper holes through the plate 9, and are 40 provided at their free ends with pull rings 14.

In operation, the fan 6 may be driven by a motor, or may be rotated by the draft created by the difference in air pressure on 45 opposite sides thereof. It is apparent that in order to lessen or increase the draft to any desired degree, it is but necessary to pull the rings 14. By making the weight of the rings sufficient, they may balance the weight 50 of the shutters in any position of the latter.

I claim:

1. A device of the class described comprising a pair of spaced apart plates rigidly connected, said plates provided with circular 55 openings, a cylindrical tube surrounding one of said openings and rigid with one of said plates, a fan rotatably mounted in said tube, a pair of substantially semi-circular shutters pivotally mounted between said plates 60 on different axes, and means for regulating said shutters to control the opening of said tube.

2. A device of the class described comprising a pair of spaced apart plates rigidly connected, said plates provided with circular openings, a cylindrical tube rigid with one of said plates and surrounding one of said openings, a fan rotatably mounted in said tube, opposed shutters pivotally mounted between said plates on different axes, drums rigid with said shutters about the pivotal axes of said shutters, flexible cables attached to said drums and partly wound thereon, said cables passing out of and below said plates, 70 and rings upon the ends of said cables.

In witness whereof I affix my signature.
HENRY MOLENDA.
